UNITED STATES PATENT OFFICE

102,805

DESIGN FOR A TABLE OR SIMILAR ARTICLE

Parker Smith, Dallas, Tex.

Application August 29, 1936, Serial No. 64,638

Term of patent 14 years

To all whom it may concern:

Be it known that I, Parker Smith, a citizen of the United States, residing at Dallas, in the county of Dallas and State of Texas, have invented a new, original, and ornamental Design for a Table or Similar Article, of which the following is a specification, reference being had to the accompanying drawing, forming part thereof.

The figure is a view in perspective of a table or similar article showing my new design.

The characteristic feature of the design resides in the fanciful representations of the products of the State of Texas upon the table top, as shown.

I claim:

The ornamental design for a table or similar article, as shown and described.

PARKER SMITH.
